UNITED STATES PATENT OFFICE.

ANTHONY C. RADER, OF ALTA, IOWA.

FEEDER FOR FOUNTAIN-PENS.

1,359,918.

Specification of Letters Patent. Patented Nov. 23, 1920.

Original application filed November 17, 1919, Serial No. 338,445. Divided and this application filed March 29, 1920. Serial No. 369,511.

To all whom it may concern:

Be it known that I, ANTHONY C. RADER, a citizen of the United States, residing at Alta, in the county of Buena Vista and 5 State of Iowa, have invented a new and useful Feeder for Fountain-Pens, of which the following is a specification.

This invention relates to new and useful improvements in fountain pens, and more 10 particularly to one of the self-filling type, adapted to permit filling thereof, without the use of the ordinary and well known rubber sack or bulb as an ink container, the invention comprehending an improved feeder 15 or feeding device for the ink whereby the same may be caused to flow freely to the pen point or nib, but prevented from dropping or spilling therefrom and blotting the paper.

The invention comprises a divisional part 20 of my application Serial No. 338,445, filed November 17, 1919, and an improvement thereon with respect to the feeding device therefor so as to prevent ink from exuding therefrom, to provide a pen which is absolutely leak-proof, simple and inexpensive of 25 production and durable in use.

Heretofore all fountain pens in general, and so far as I am aware, and have investigated, as they empty and the air rushes in 30 to displace the ink, cause a blot of ink to fall on the paper and especially the last drop, instead of being used up. The ink also tends to harden at the feeding device or 35 passage, as well as between the pen point or near the end of the feed, thus preventing the proper and the free flow of ink, or entirely cutting off the flow.

It is also an object of the invention to 40 provide a device by which the greater portion of the back of the pen point is exposed at the concaved side, so as to facilitate the cleaning and in addition to insure uniformity of flow of the ink at either side, the construction being such as to hold back the ink 45 whereby ordinary jar or shaking of the pen and ink as in writing, will not cause the ink to fall off while the pen will always be provided with an even flow of ink when left for some time without using.

With the above and other objects in view 50 which will appear as the description proceeds, the invention resides in the combination and arrangement of parts and in the details of construction hereinafter described 55 and claimed, it being understood that within the scope of what is claimed, changes in

the precise embodiment of the invention shown can be made without departing from the spirit of the invention.

In the accompanying drawings:

Figure 1 is a side elevation of my improved fountain pen showing the feeding device in longitudinal section at the pen point;

Fig. 2 is a similar view showing the reversed side of the feed at the back or concaved sides of the pen point nib;

Fig. 3 is a detailed rear elevation of the feeder;

Fig. 4 is a side view thereof; and

Fig. 5 is a transverse sectional view taken 70 on the line 5—5 of Fig. 4.

Referring to the drawings in detail, in which like reference characters designate corresponding parts throughout the several views; the numeral 10 designates the cylindrical barrel of the fountain pen, which is provided with the filling means described in connection with my prior application above referred to. The barrel is provided with the cap 11 at one end confining the 75 filling means when the latter is not in use, and at the opposite end with a cap 12 which is designed to be engaged over the pen point 17 when the pen is not in use and over the cap 11 when the pen is in use, the cap 12 80 having internal threads spaced from the open end thereof engaging coöperating external threads on the end of the barrel 10 as indicated at 13, although it is to be understood that any other form of connection or 85 method of applying the cap 12 may be employed if desired. The barrel 10 is internally threaded, preferably to receive the external threads of a plug 14, as shown at 15, the plug being preferably beaded and apertured as shown at 16 to constitute a pen 90 holder for the point 17.

The pen point or nib 17 is held in the aperture 16 in conjunction with a feeding device 18 preferably of semi-circular cross 100 section and provided with a longitudinal groove or channel 19 extending to its upper end for communication with the interior of the barrel whereby the ink may flow into said groove or channel. The opposite end 105 of the groove or channel terminates at a spaced distance from the pointed end 20 of the feeder, that is short of or within the anchor head 21 provided at the discharge end. The anchor head provides the opposed 110 grooves or recesses 22 at either side of the reduced portion of the feed shank or feeder,

thus provided and against which the pen point 17 is fitted in order to be engaged in the cylindrical opening 16 leading from the interior of the barrel 10 which is adapted for containing the writing fluid or ink. These recesses 22, provide means for receiving excess or surplus ink, that might come out between the pen and the feeding device.

It should also be noted that the shank portion of the feeder is very narrow, with comparison to the width of the pen point at the concaved side or back thereof, so as to expose the greater portion of the pen point to facilitate cleaning thereof as well as to provide relatively wide spaces or cells for receiving the surplus ink therein so as to obviate the possibility of this ink dropping off and blotting the paper. This narrow shank portion preferably extends into the plug a slight distance, in order to insure proper feed, the formation of the shank or feeder being tapered above the narrow flat portion which is centrally disposed between the sides of the pen point or nib. The shank portion is further provided with a plurality of transverse openings 23, preferably three in number and located intermediately of the edge portions thereof at the front and back, in order that the ink may flow through so as to secure even distribution or flow at either side and further preventing the ink forming and dropping off.

By the above construction, I am able to obviate the ink dropping off and blotting the paper, as it usually happens in fountain pens that as they empty, the air rushes in to cause a blot of ink to fall on the paper. With this device, the last drop of ink is held by the anchor feed and is all used up instead of falling in a blot, the device providing more room on the pen point or at either side of the feeder for extra ink, while the anchor points and the recesses or grooves formed thereby, hold the ink back. This obviates the possibility of overflow resulting in the ink falling off and by reason of making the shank portion of the feeder relatively narrow, it is very easy to clean out any ink that might dry in the sockets or recesses formed by the construction, when not used for some time and should there be more flow on one side than on the

other, the small holes or apertures will allow the ink to flow on the side at which there is less ink, thus insuring uniform feed and preventing the ink from dropping off. There is a certain amount of adherence or cohesion between the ink through the openings at the opposite sides of the feeder or shank thereof, which will prevent the ink from falling off and a uniform feed will always be insured even though left some time without using. As the device does not cover much of the pen point or nib, it prevents the ink from drying up under it and stopping the flow.

Having thus described the invention what I claim is:

1. A feeder for fountain pens, comprising a cylindrical body merging into a reduced shank terminating in a single arrow shaped head, the shank being approximately rectangular in cross section, and of unequal transverse dimensions, the shank having a plurality of spaced openings extended entirely therethrough and disposed in a line extending longitudinally of the shank, the openings being spaced from both longitudinal edges of the shank and the axes of the openings being disposed parallel to the minor transverse dimension of the shank.

2. A feeder for fountain pens, comprising a cylindrical body merging into a reduced shank terminating in a single arrow shaped head, the shank having a curved edge prolonged to the top of the head and defining a point, the body and the shank having a superficial longitudinal duct extended upon the head and terminating in spaced relation to the point, the shank being approximately rectangular in cross section, and of unequal transverse dimensions, the shank having a plurality of spaced openings extended entirely therethrough, the openings being spaced from both longitudinal edges of the shank and the axes of the openings being disposed parallel to the minor transverse dimension of the shank.

In testimony that I claim the foregoing as my own, I have hereto affixed my signature in the presence of two witnesses.

ANTHONY C. RADER.
